(57) **CLAIM**

The ornamental design of a dance pole, as shown and described.

DESCRIPTION

FIG. 1 is a side elevational view of a dance pole showing my new design with the dance pole being shown in a retracted state;

FIG. 2 is a top plan view thereof;

FIG. 3 is a bottom plan view thereof;

FIG. 4 is a perspective view thereof;

FIG. 5 is a perspective view thereof with the dance pole being shown in an extended state;

FIG. 6 is a side elevational view of the dance pole shown in an extended state;

FIG. 7 is an enlarged perspective view of three segments of the dance pole shown as being separated from each other;

FIG. 8 is an enlarged side view of the segments of the dance pole of FIG. 7;

FIG. 9 is a top plan view of the segments of the dance pole of FIG. 8;

FIG. 10 is a bottom plan view of the segments of the dance pole of FIG. 8;

FIG. 11 is an enlarged perspective view of the segments of the dance pole of FIG. 7 with the top segment being shown in an extended state;

FIG. 12 is an enlarged side elevational view of the segments of the dance pole of FIG. 7 with the top segment being shown in an extended state; and,

FIG. 13 is a greatly enlarged fragmentary perspective view of a top portion of the dance pole of FIG. 1.
